Charles H. Chapin

Inventor

David Saunderson

United States Patent Office.

DAVID SAUNDERSON, OF ST. LOUIS, MISSOURI, ASSIGNOR TO JOHN RINGEN
OF SAME PLACE.

Letters Patent No. 65,836, dated June 18, 1867.

IMPROVED MODE OF BOXING OIL-CANS.

The Schedule referred to in these Letters Patent and making part of the same.

TO ALL WHOM IT MAY CONCERN:

Be it known that I, DAVID SAUNDERSON, of the city and county of St. Louis, State of Missouri, have invented a new and useful Method for Boxing Oil-Cans, called "Saunderson's Can-Box;" and I do hereby declare the following is a full and exact description of the same, reference being had to the annexed drawing, and—

The nature of my invention consists in providing the box with a wedge, so as to tighten the can in the box when being shipped, and to prevent the nozzle from injury, and when the can is to be emptied of its contents the wedge serves to throw the nozzle out from the surface of the box, so the contents may run out freely.

Figure 1 represents a perspective view of "Saunderson's can-box," of which A is a block or wedge; B is a square wooden box, with two apertures C D, and a small round hole, E; F is a metallic can with a nozzle, G.

Now, when the wedge is put in at the aperture C, it presses the can down on the bottom of the box B, and depresses the nozzle G beneath the level of the top of the box, in which case it may be shipped with safety to the nozzle G.

When the can is to be emptied of its contents, remove the wedge A and place it in the bottom at D, and the can is elevated and the nozzle is projected from the wooden box, in which case the fluid may be poured from the can without interruption from the box.

Now, what I claim as my invention, and for which I ask Letters Patent of the United States to be granted, is—

The combination of the wooden box B, can F, and wedge A, as above named and described, and for the purposes set forth.

DAVID SAUNDERSON.
